METHODS AND APPARATUS FOR ENHANCED SPUTTER-ION PUMP OPERATION

Sherman L. Rutherford, Palo Alto, Calif., assignor to Varian Associates, Palo Alto, Calif., a corporation of California

Filed Aug. 14, 1961, Ser. No. 131,225
13 Claims. (Cl. 230—69)

This invention relates to methods and apparatus for enhancing the pumping of sputter-ion pumps. More particularly, this invention relates to enhanced hydrogen and hydrogen isotope pumping with sputter-ion pumps.

The pumping mechanism for such chemically active gases as oxygen and nitrogen in cold-cathode gas discharge sputter-ion pumps of the type described and claimed in U.S. Patent No. 2,993,638, issued to L. D. Hall et al. on July 25, 1961, is dominated by chemical combination with sputtered active metal atoms from the cathodes. These gases cause cathode material such as, for example, titanium or zirconium to be sputtered rapidly enough that approximately one atom of gas is pumped for each ion formed in the discharge. Most of the pumped oxygen and nitrogen reside on the anode of the pump in chemical combination with sputtered cathode material.

In contrast, hydrogen and its isotopes are so light that their ions produce comparatively little sputtering. Despite this, it is found that present sputter-ion pumps employing cathodes made of, for example, titanium or zirconium generally display a hydrogen pumping speed which is more than twice that for oxygen or nitrogen. It has also been established experimentally that most of the hydrogen is pumped by diffusion into the cathodes rather than by chemical combination at the anode. In addition, significant residual pumping (continued pumping after the discharge voltage is removed) occurs, indicating that hydrogen can be pumped by direct molecular contact with the cathode surfaces without the necessity for dissociation, ionization or ion burial.

These observations suggest that two factors of dominant importance in the pumping of hydrogen are (1) cathode surface conditions which affect the rate at which incident molecular hydrogen is adsorbed, and (2) solubility of the bulk cathode material for hydrogen. Surface conditions are strongly affected by oxide films and layers of adsorbed gas, while solubility is influenced by temperature, pressure and impurities or defects in the cathode material.

The present invention deals with the first of the above factors in that it provides a method of sputter-ion pump treatment which results in a dramatic enhancement of the pump's hydrogen pumping speed. The pumping of a gas which is chemically inert with respect to the cathode material and whose molecules have a greater mass than those of hydrogen produces a surface cleaning effect on the cathodes of typical sputter-ion pumps. This cleaning effect greatly increases the cathode's hydrogen sorption rate and thus provides a pump with greatly increased hydrogen pumping speed (typically 10 times the normal hydrogen pumping speed).

This invention also deals with the second of the above factors in that it provides a method and apparatus for further increasing the hydrogen pumping throughput at high pressures (above 10^{-4} mm. Hg). Ordinarily, sputter-ion pump operation at high pressures of hydrogen is difficult because the pump current is proportional to pressure and the increased power which must be dissipated causes cathode heating with subsequent thermal re-evolution of the previously absorbed hydrogen. The novel method and apparatus of this invention greatly reduces the high pressure power input to the pump to thereby

2

reduce hydrogen re-evolution while still retaining a steady and relatively high value of pumping speed. This high pumping speed is possible because of the molecular hydrogen pumping characteristic of sputter-ion pumps.

5 The object of the present invention therefore is to enhance the pumping of hydrogen and hydrogen isotopes with sputter-ion pumps.

One feature of the present invention is the provision of a method and means for treating sputter-ion pump cathodes by pumping a gas which is chemically inert with respect to the cathode material and whose molecular mass is greater than that of hydrogen to provide a pump exhibiting a greatly increased hydrogen pumping speed.

10 Another feature of the present invention is the provision of a method and means of the above featured type wherein the treatment of the sputter-ion pump cathodes is made with argon.

15 Another feature of the present invention is the method and means for maintaining a constant average pump input power during high pressure operation to prevent excessive cathode temperatures and associated hydrogen re-evolution.

20 Still another feature of the present invention is the provision of a method and means for producing an intermittent energization of a sputter-ion pump thereby reducing the pump's input power while retaining a steady and relatively high value of hydrogen pumping speed.

25 These and other features and advantages of the present invention will become more apparent upon a perusal of 30 the following specification taken in connection with the accompanying drawings wherein,

FIG. 1 is a diagram showing the variation of hydrogen pumping speed with time due to hydrogen pumping and argon sputtering,

35 FIG. 2 is a diagram showing the residual hydrogen pumping characteristic of a sputter-ion pump,

FIG. 3 is a diagram indicating the relative portions of 40 hydrogen pumping speed which are due to ion pumping and molecular pumping for an argon treated sputter-ion pump,

FIG. 4 is a diagram showing the dependence of temperature of the hydrogen solubility rate for a sputter-ion pump,

45 FIG. 5 is a diagram showing power versus pressure curves for a typically operated sputter-ion pump and one operated in accordance with one embodiment of the present invention, and

50 FIG. 6 is the circuit diagram of a power supply which supplies a pulsed output voltage and a constant average power to a sputter-ion pump operating at high pressure.

Referring now to FIGS. 1-3 there are shown diagrams which illustrate the dramatic effect that cathode surface conditions have on the hydrogen pumping speed of a sputter-ion pump. The diagram of FIG. 1 represents 55 a particular sputter-ion pump's hydrogen pumping speed in liters per second and length of pumping time in hours plotted on the vertical and the horizontal axes, respectively. The pumping measurements were taken for a sputter-ion pump whose cathodes had been exposed to air and while maintaining a hydrogen environment pressure of approximately 1×10^{-5} mm. of Hg within the sputter-ion pump envelope. The dotted curve 11 shows a constant pumping speed of about 2 liters per second for the first 50 hours of operation. The dotted curve 60 then indicates a gradual speed increase between 50 and 80 hours of operation time and then a leveling off to a constant pumping speed at approximately 4 liters per second. This modest speed increase is probably due to increased cathode permeability which results from rifts and cracks created in the cathode by the extended period of hydrogen ion bombardment.

65 The hiatus 12 between the dotted curve 11 and the

solid curve 13 represents a period of several hours when the sputter-ion pump is operated in an argon environment produced by the introduction of argon into the pump envelope. The solid curve 13 shows an extremely high hydrogen pumping speed of over 14 liters per second when the pump was returned to a hydrogen environment and measurements taken under the same conditions as those for dotted curve 11. This extremely high pumping speed then declined gradually over a period of approximately 30 hours to reach the steady state pumping speed of approximately 11 liters per second illustrated in the last portion of the solid curve 13.

Thus, the curves of FIG. 1 illustrate the greatly increased hydrogen pumping speed which is obtainable after a sputter-ion pump has operated in an argon environment. This increased speed results from the more rapid rate of hydrogen molecule diffusion into the pump cathode which is possible after the ion pump's reactive cathode surfaces have been sputtered clean of impurities by the bombarding heavy argon ions. The "intrinsic" pumping speeds are enhanced even more than the measured ones shown in FIG. 1 since the conductance effects are increased at the higher pumping speeds. The extremely high hydrogen pumping speed immediately following the argon treatment results from the pumping contribution made by the freshly sputtered cathode material which has collected on the sputter-ion pump's anode and envelope surfaces. When this material has become saturated with hydrogen, pumping occurs only into the cleaned cathode surfaces and accordingly pumping speed falls to the lower steady state value illustrated by the solid curve 13. Also, the high value of steady state pumping speed illustrated by the solid curve 13 of FIG. 1 shows that the limited cathode sputtering produced by the lighter hydrogen ions is sufficient to maintain a clean cathode in spite of the limited amount of impurities in the hydrogen environment. This extremely high hydrogen pumping speed will exist until the pump cathodes have again been exposed to gases (oxygen, air, etc.) which are chemically active with respect to the cathode material. Such an exposure would contaminate the cathode surfaces making another cleaning treatment necessary.

Argon gas is preferred as a cleaning agent because of its availability and ease of handling. However, other gases which are chemically inert with respect to the cathode material and which are of a greater molecular mass than hydrogen will also produce sufficient cathode sputtering to provide a clean cathode surface. Furthermore, combinations of cleaning agent gases can be used.

FIG. 2 shows a curve 14 which illustrates the residual pumping characteristic which a particular sputter ion pump exhibits for hydrogen. Residual hydrogen pumping speed in liters per second is plotted on the vertical axis and time in seconds after turning off the pump anode voltage is plotted on the horizontal axis. The particular sputter-ion pump used to obtain the data plotted in FIG. 2 had titanium cathodes which had been argon sputtered as indicated above and was operated while a hydrogen leak into the pump envelope was held constant. Initial conditions for the curve were a pumping speed of 15 liters per second and a pressure of 4×10^{-5} mm. of Hg. As shown by the curve 14 the initial value of the residual pumping speed was about 95% of the pumping speed while the pump discharge was in operation. The time required for the residual pumping speed to fall by a factor of e was 1×10^{-3} seconds.

Thus, a sputter ion pump will continue to pump hydrogen at a significant rate for some time after its gas discharge has been extinguished by removing anode voltage. The gradual deterioration of the residual hydrogen pumping speed is attributed to a contamination of the pump cathode surfaces by impurities in the hydrogen supply.

The diagram of FIG. 3 shows hydrogen pumping speed

curves of a particular sputter-ion pump before and after argon treatment. Hydrogen pumping speed in liters per second is plotted on the vertical axis vs. relative time on the horizontal axis. Dotted curve 15 represents the pumping speed of a sputter-ion vacuum pump before treatment. As shown, the pump exhibited an initial steady state pumping speed of about two liters per second under normal operating voltage. At point 16 the pump's operating voltage was reduced by 50% which resulted in a corresponding reduction in pumping speed to about one liter per second. At point 17 the full normal operating voltage was again applied and the steady state pumping speed returned to its former value of two liters per second.

The solid curve 18 represents the hydrogen pumping speed of the same sputter-ion vacuum pump after having been treated by several hours of argon pumping. As shown, an initial steady state pumping speed of about 14 liters per second was obtained with normal operating voltage. At point 19 the pump's operating voltage was reduced by 50% and a corresponding reduction in steady state pumping speed to about 13 liters per second occurred. At point 21 normal pump voltage was again applied and the steady state pumping speed returned to its former value of about 14 liters per second.

An examination of the hydrogen pumping speed curves 15 and 18 shows that a 50% reduction in operating voltage resulted in a pumping speed reduction of about one liter per second for both the treated and the untreated sputter-ion pump. This occurred in spite of the fact that the steady state hydrogen pumping speed for the treated pump was some 7 times the pumping speed for the untreated pump. It thus appears that the amount of pumping speed produced by the pump's normal ion pumping mechanism is the same for the treated or untreated pump. This is represented in the case of the treated sputter-ion pump by the area between the solid curve 18 and a horizontal line 22 drawn at approximately 12 liters per second. The remainder of the total pumping speed achieved by the treated sputter-ion pump is represented by all of the area below the horizontal line 22 and amounts to a constant pumping speed of about 12 liters per second. This pumping speed is apparently independent of the pump operating voltage and is attributed to molecular pumping wherein free molecules of hydrogen are freely adsorbed onto the clean cathode surfaces where they are dissociated and diffuse into the cathode. In the case of the untreated pump the presence of gases exhibiting a reaction with the cathode materials apparently creates a layer on the cathodes which limits this type of molecular pumping.

FIGS. 4 and 5 illustrate the second important factor in the pumping of hydrogen, i.e., the solubility of the bulk cathode material for hydrogen. FIG. 4 shows the dependence of this solubility upon the temperature of the cathode material with curve 23 plotting hydrogen pumping speed in liters per second on the vertical axis and the cathode temperature in degrees centigrade on the horizontal axis. The measurements were taken at a constant pressure of 5×10^{-5} mm. Hg and as shown the pump exhibits a substantially constant pumping speed of about 2 liters per second for cathode temperatures up to about 280° centigrade. At that point the pumping speed falls off rapidly to become insignificant at 400° centigrade. This decrease in hydrogen pumping speed is attributed to the decreased solubility of the cathode material for hydrogen.

FIG. 5 is a diagram of various power operating curves for a typical sputter-ion pump (nominal pumping speed 5 l./s.) with pump input power in watts plotted on the vertical scale and pump operating pressure plotted on the horizontal scale. The dot-dash curve 24 represents the power input of an unlimited power supply. As shown the power input rises linearly with increasing pressure. Solid curve 25 shows the power curve for a typically used sputter-ion power supply having some type of current limiting

device to limit power input to the pump in the pressure range of its starting condition (reduction of pump pressure from about 10^{-2} mm. Hg to below 10^{-4} mm. Hg). Such current limited power supplies are used to prevent high power thermal damage to the pump in this starting pressure region.

Some difficulty is experienced in the pumping of hydrogen with power supplies of the type represented by the solid curve 25. The difficulties result from the large "power hill" 27 which must be overcome in order to start the pump. The high power that must be dissipated during operation in the upper portion of the "power hill" 27 produces high cathode temperatures. These temperatures frequently rise above the critical value causing a reduction in the solubility of the cathode material for hydrogen and a corresponding increase in re-evolution of hydrogen to thereby greatly reduce the pump's hydrogen pumping speed. This greatly prolongs the time necessary to start the pump. For example, in normal operation using a power supply with power characteristic shown by the solid curve 25 the time for starting a typical sputter-ion pump in a hydrogen atmosphere can be over one hour while the starting time for the same pump with other gases would be a few minutes.

Dotted curve 26 represents the power curve for a power supply operated in accordance with the present invention. The input power to the pump rises linearly with increasing pressure up to about 10^{-4} mm. of Hg and then levels off to supply a constant average power with respect to pressure in the pressure region of the pump's starting condition.

By eliminating the "power hill" in the pump's starting pressure range, the problem of heated cathodes and reduced solubility is eliminated and pump starting time is greatly reduced (typically to a few minutes).

Referring now to FIG. 6 there is shown a power supply circuit for providing a sputter-ion pump with a substantially constant average power input with respect to pressure in the pressure region between 10^{-2} mm. of Hg and 10^{-4} mm. of Hg. The positive lead 31 of a conventional power supply 32 is connected to the anode 33 of a gas diode 34 whose cathode electrode 35 is connected through a series resistor 36 to the anode 37 of a thyatron 38. The cathode electrode 39 of thyatron 38 is connected to the anode 41 of a sputter-ion pump 42 whose cathode electrodes 43 are connected to the pump envelope 44. A parallel resistor 45 is connected directly between the anode 37 and the cathode 39 of the thyatron 38 while a capacitor 46 is connected between ground and the junction between series resistor 36 and the thyatron anode 37. The primary winding 47 of a transformer 48 is connected to the A.C. power supply 32 through a voltage regulator 49. The secondary winding 51 of the transformer 48 is connected in series with a resistor 52 and D.C. power supply 53 between the grid 54 and the cathode 39 of thyatron 38.

In operation of the circuit of FIG. 6 the A.C. voltage applied to the anode 33 of the diode 34 and the A.C. voltage applied to the grid 54 are 180° out of phase. The diode 34 conducts only on positive cycles to provide a pulsed D.C. current which charges the capacitor 46 to establish a voltage at the anode 37 of the thyatron 38. When the capacitor 46 has been charged to a sufficiently high voltage the thyatron 38 will fire as the A.C. voltage applied to the thyatron grid 54 is going positive. Now, if the sputter-ion pump 44 is operating at high pressure (between 10^{-4} mm. Hg and 10^{-2} mm. Hg, for example) the impedance between the pump anode 41 and the pump cathodes 43 is very small. Therefore, the capacitor 46 will discharge through the conducting thyatron 38 and sputter-ion pump 42 to establish a gas discharge between the pump anode 41 and pump cathodes 43. As the capacitor 46 discharges the voltage at the thyatron anode 37 is reduced to cut off the thyatron 38 and de-energize the pump anode 41.

Thus the circuit of FIG. 6 will provide intermittent pump operation at high pressures thereby reducing the pump input power. At the same time the hydrogen pumping speed of the sputter-ion pump 42 remains high as the intermittent operation of the gas discharge provides sufficient ion sputtering to maintain clean pump cathodes while hydrogen pumping continues even during the gas discharge off periods due to the residual pumping effect shown in FIG. 2. The particular voltage duty cycle applied to the pump anode 41 can be established by adjusting the time constant of the capacitor 46. The pump input power reduction is increased by extending the off portion of the pump's duty cycle and sputter-ion pumps have maintained high hydrogen pumping speeds while operating, for example, on a duty cycle having off portions which were about seven times as long as the on portions.

However, when the sputter-ion pump 42 is operating at low pressure (below 10^{-4} mm. Hg, for example) the impedance of the gas discharge is high so that the capacitor can not fully discharge in the periods between charging pulses supplied by the diode 34. Therefore the thyatron 38 is not cut off and a rippling D.C. voltage is applied to the pump anode 41 through the continuously conducting thyatron 38. And, at extremely low pump pressures the pump impedance can become so large that the current drawn by the pump 42 is insufficient to maintain the discharge in the thyatron 38. The D.C. voltage will then be applied to pump anode 41 through the high resistance (100K, for example) parallel resistor 45.

The pulsing circuit of FIG. 6 is a preferred embodiment because of the large pump input power reduction it provides. However, other types of power reducing circuits can also be used. For example only, the series resistor 36 can be replaced with an inductance which would also reduce pump input power in addition to reducing power lost in the power supply circuit.

Many other changes could be made in the above construction and many apparently widely different embodiments of this invention could be made without departing from the scope thereof. It is therefore intended that all matter contained in the above description or shown in the accompanying drawings shall be interpreted as illustrative and not in a limiting sense.

45 What is claimed is:

1. The method of treating a sputter-ion pump having anode and cathode electrodes adapted to maintain a gas discharge within a vacuum envelope, said method comprising the steps of initiating a gas discharge between said anode and cathode electrodes, introducing into said envelope a gas which is chemically inert with respect to said cathode electrode and whose molecules are of a greater mass than those of hydrogen, and bombarding said cathode electrode with ions of said gas so as to cause sputtering of said cathode electrode thereby providing a pump exhibiting a greatly increased pumping speed for hydrogen and its isotopes.

2. The method according to claim 1 wherein said gas introduced into said envelope is argon.

3. The method of treating a sputter-ion pump having anode and cathode electrodes adapted to maintain a gas discharge within a vacuum envelope, said method comprising the steps of introducing into said envelope a gas which is chemically inert with respect to said cathode electrode and whose molecules are of a greater mass than those of hydrogen, initiating a gas discharge between said anode and cathode electrodes, and bombarding said cathode electrode with ions of said gas so as to cause sputtering of said cathode electrode thereby providing a pump exhibiting a greatly increased pumping speed for hydrogen and its isotopes.

4. The method according to claim 3 wherein said gas introduced into said envelope is argon.

5. The method of operating a sputter-ion pump having anode and cathode electrodes adapted to maintain

a gas discharge within a vacuum envelope, said method comprising the steps of evacuating said vacuum envelope to a pressure below 10^{-2} mm. Hg, applying a pulsed voltage to said anode electrode of said sputter-ion pump, and said pulsed voltage having a duty cycle wherein the off portion is greater than the on portion.

6. The method of operating a sputter-ion pump having anode and cathode electrodes adapted to maintain a gas discharge within a vacuum envelope, said method comprising the steps of initiating a gas discharge between said anode and cathode electrodes, introducing into said envelope a gas which is chemically inert with respect to said cathode electrode and whose molecules are of a greater mass than those of hydrogen, and bombarding said cathode electrode with ions of said gas, introducing hydrogen into said vacuum envelope, and applying a pulsed voltage to said anode electrode of said sputter-ion pump.

7. The method according to claim 6 wherein said inert gas introduced into said envelope is argon.

8. The method of operating a sputter-ion pump having anode and cathode electrodes adapted to maintain a gas discharge within a vacuum envelope, said method comprising the steps of introducing into said envelope a gas which is chemically inert with respect to said cathode electrode and whose molecules are of a greater mass than those of hydrogen, initiating a gas discharge between said anode and cathode electrodes, and bombarding said cathode electrode with ions of said gas so as to cause sputtering of said cathode electrode, introducing hydrogen into said vacuum envelope, and applying a pulsed voltage to said anode electrode of said sputter-ion pump.

9. The method according to claim 8 wherein said inert gas introduced into said envelope is argon.

10. The method of treating a sputter-ion pump having anode and cathode electrodes adapted to maintain a gas discharge within a vacuum envelope, said method comprising the steps of introducing into said envelope a gas which is chemically inert with respect to said cathode electrode and whose molecules are of a greater mass than those of hydrogen, and bombarding said cathode electrode with ions of said gas to cause sputtering of said cathode electrode thereby providing a cleaned cathode surface which exhibits a greatly increased pumping speed for hydrogen and its isotopes.

11. The method according to claim 10 wherein said gas introduced is argon.

12. An apparatus for pumping hydrogen and its isotopes comprising an anode electrode, a cathode electrode, said anode and cathode electrodes adapted to maintain a gas discharge upon energization of said anode electrode, power supply means for providing voltage to said anode electrode, power supply means for adapting said power supply means to provide said anode electrode with a pulsed voltage having a duty cycle wherein the off portion is greater than the on portion.

13. The method of operating a sputter-ion pump having anode and cathode electrodes adapted to maintain a gas discharge within a vacuum envelope, said method comprising the step of applying to said anode of said sputter-ion pump a pulsed voltage having a duty cycle wherein the off portion is greater than the on portion.
